UNITED STATES PATENT OFFICE.

ROBERT C. RUSSELL, OF PITTSBURGH, PENNSYLVANIA.

INDEX.

Application filed March 5, 1926. Serial No. 92,489.

- This invention relates to improvements in indexes and more particularly to those of the type which have become known in the art as "visible" indexes.
- 5 One object of my present invention is to so construct the index strips or elements of a visible index that they shall lie flat; be compactly assembled; so that the strips or index elements shall be readily movable or removable; so that the several strips or index elements shall have an intermeshing relation to each other, and so that the strips shall be supported, one by another when assembled in a frame or holder.
- 10 With these and other objects in view, the invention consists in certain novel features as hereinafter set forth and pointed out in the claims.
- In the accompanying drawings;
- 20 Figure 1 is a face view of a visible index illustrating an embodiment of my invention;
- Figure 2 is a sectional view on the line 2—2 of Figure 1;
- 25 Figure 2^a is a sectional view on the line 2^a—2^a of Figure 1;
- Figure 3 is a separate view of one of the index elements or strips;
- 30 Figure 4 is a view of an index element or strip adapted to receive more than a single line of index data.
- Fig. 5 is a view showing a connected series of index elements or strips.
- 35 My improved index includes a plurality of holders for receiving the strips or index elements. One such holder is indicated at 1 and it may be made of metal in the form of a slide, drawer or leaf and comprises a base 2 provided at its upper end with a shoulder 3 and at its lower end with an overlying flange 3^a. At the sides of said base are flanges 4 which overlie side portions of said base and are spaced from the latter to provide guides or ways 5 to receive end portions of index strips or elements 6 on which any suitable index data may be written or otherwise produced.
- 40 Each index strip or element 6 (which may be made of card or other suitable material) is sufficiently flexible and elastic to permit the ready insertion of its end portions into the guideways 5 or removal of the same therefrom and to enable the said index elements to lie flat in the holder. The end portions of the index elements should be caused to be disposed in the guideway with sufficient looseness to permit said elements to be read-
- ily moved in a plane substantially parallel with the face of the holder.
- 45 Each index element comprises an intermediate or body portion 7, end members 8, 8, and an elongated tongue 9 (preferably having beveled ends as at 9^a) projecting upwardly from the upper edge of the body portion 7 of the element and having beveled or inclined upper edge portions indicated at 10. The upper portions of the end members 8, 8, are in alinement with the body portion 7 and depend below the plane of the lower edge of the latter to form depending tongues 11, the outer end of which may be beveled as at 12 and the inner end beveled or rounded, as at 13, while the lower edge of each tongue 11 may be beveled as at 14. The intermediate body portion and the upper portions of the end members of each index member receive 50 a line of index matter as clearly shown in Figure 1. It will be understood however, that the portions 7 and 8 of each index element may be made sufficient in width to accommodate a plurality of lines of index data. In Figure 5 an index element 6^a adapted for the reception of two lines of index data, is illustrated.
- 55 A number of connected index elements 6 may be cut from a single sheet, as shown in Figure 5, so that the typewriting of the index data on the elements may be facilitated, and the elements 6 may be afterwards separated and ready for insertion into the holder 1.
- 60 In inserting the index elements into the holder, the end portions of a strip constituting an index element will first be slipped into guideways 5 of the holder, preferably at a point somewhat above a previously inserted index element, and then moved downwardly so that the tongues 11 will become disposed behind or under the end portions 8 of the previously inserted index element and so 65 that the body portion 7 of the index element being inserted will become disposed in front of the elongated tongue 9 of the next lower index element. The rounded inner ends 13 of the tongues 11 cooperating with the beveled ends 9^a of the tongue 9 of an adjacent element 6 will facilitate the insertion of said tongues 11 behind portions 8 of an adjacent element, and by beveling the upper edge portion of the tongue 9 of an index element, the disposing 70 of the portion 7 of an upper element 6 in front of said tongue 9 will be facilitated.
- 75 It will be understood that when the index

elements are assembled in the holder, they will be supported by each other and there will be an intermeshing of the several index elements. The index elements will lie flat; 5 they are compactly arranged; one or any desired number of them may be readily moved relatively to the others to permit the insertion of a new strip or element and then moved to normal assembled position, and any one or 10 more of the index elements may be removed from the holder and replaced by new ones as occasion may require.

Having fully described my invention what I claim as new and desire to secure by Letters-Patent, is;—

1. In an index, a series of index elements, each comprising a body portion, end members, a tongue above said body portion, and tongues depending from said end members 20 to clear the first-mentioned tongue on a lower index element and pass behind the end members of said lower element to rest upon the same, said last mentioned tongues having beveled inner ends.
- 25 2. In an index, a series of index elements, each comprising a body portion, end members, a tongue above said body portion, and tongues depending from said end members to clear the first-mentioned tongue on a lower index element and pass behind the end members of said lower element to rest upon the same, said last mentioned tongues having

beveled inner ends, and said first mentioned tongue having beveled ends.

3. In an index, a series of index elements, 35 each comprising a body portion, end members, a tongue above said body portion, and tongues depending from said end members to be engaged behind the end members of a lower element and interlock the series of elements, said last mentioned tongues having beveled inner ends and beveled lower edges.

4. In an index, a series of index elements, 40 each comprising a body portion, end members, a tongue above said body portion to engage behind the body portion of an upper index element, and tongues depending from said end members, said last mentioned tongues having beveled inner ends and the upper edge of said first mentioned tongue 45 being beveled.

5. In an index, the combination, of a plurality of movable index elements, each comprising a body portion, end members, a tongue above said body portion and disposed 50 behind the body portion of an upper index element, and tongues depending from the end members of each index element and entering behind end members of a lower index element, each face of each element being in a 55 single plane throughout its extent.

In testimony whereof, I have signed this specification.

ROBERT C. RUSSELL.
